UNITED STATES PATENT OFFICE.

ALANSON C. ESTABROOK, OF FLORENCE, MASSACHUSETTS, ASSIGNOR TO
THE FLORENCE MANUFACTURING COMPANY, OF SAME PLACE.

DENTAL-PLATE BRUSH.

SPECIFICATION forming part of Letters Patent No. 335,345, dated February 2, 1886.

Application filed June 13, 1885. Serial No. 162,654. (No model.)

To all whom it may concern:

Be it known that I, ALANSON C. ESTABROOK, of Florence, (town of Northampton,) in the county of Hampshire and State of Massachusetts, have invented certain new and useful Improvement in Dental-Plate Brushes; and I do hereby declare that the following specification, taken in connection with the drawings furnished, and forming a part of the same, is a clear, true, and complete description of my invention.

Various forms and kinds of brushes have been heretofore devised with more or less reference to their use in cleansing false teeth detached from the mouth. So far as I know, all such brushes have embodied tufts of bristles or other suitable material arranged in masses, substantially as in an ordinary tooth-brush, although in some cases an isolated group or mass of tufts has been located at the tip of the handle, the brush at its head being of the usual tooth-brush form.

A brush embodying the main feature of my invention has two or more masses of tufts of bristles on the head of the brush, and these are separated by one or more clearing-spaces, these latter being of such width that the coincident walls of bristles in any two masses may be simultaneously used for simultaneously cleansing either the two sides of a dental plate at and near its edge, or in cleansing both sides of such teeth as are mounted thereon. For obtaining specially desirable results, one of these masses of bristles is considerably longer than the other, and in its best form said longer mass is tapered or in the form of a blunt wedge, and, while this longer mass is preferably located near the outer end of the brush-head, it may, with fair results, be located at the opposite or inner side of a clearing-space, so as to be at the inner end of the brush-head or between two other masses.

To more particularly describe my invention I will refer to the accompanying drawings, in which Figure 1 is a side view of a brush embodying my invention in what I deem its best form for general use. Fig. 2 is a front view of the same. Fig. 3 is a side view of a brush embodying three masses of tufts and two clearing-spaces.

The brush-head *a* and handle *b* in their best

form are integral, and are preferably composed of bone, although other well-known and suitable materials may be employed. The form of the handle and head may be indefinitely varied. The main mass *c* of bristles correspond in the size of its tufts, and in their general arrangement, and in the form of the mass, with a corresponding portion of a tooth-brush in any of its general forms, and said mass may either be flat-faced, as shown at *c*, or convex laterally, as shown at *c'*, Fig. 3. The bristles or equivalent material should be quite coarse and stiff, especially those adjacent to the clearing-spaces, because the sides of the bristles at those points are made to do active cleansing service, as well as their tips. The mass of tufts *d* should always be composed of very coarse, tough, stiff material, and it is essentially separated from the mass *c* by the free clearing-space *e*. As shown in the drawings, Figs. 1 and 2, the mass *d* is smaller than the mass *c*, and the former is at the outer end of the head; but it is to be understood that they may be reversed in position without departure from my invention, although in such a brush the relative arrangement shown is preferred.

This combination in a tooth-brush or in a dental-plate brush of two compact masses of tufts of bristles, separated by a clearing-space, is, I believe, a broadly novel feature, in the construction of brushes, and enables the brush to be used in a novel manner. It is well-known that front teeth are thinner than double teeth, and it will be obvious that with this clearing-space a little narrower than the average thickness of double teeth, and with the handle standing at right angles to the line of double teeth, and the latter snugly embraced between the coincident surfaces of the clearing-space, a lateral reciprocation of the brush will simultaneously cleanse both sides of each tooth, the plate inside of said teeth close to their bases, and also the gum surface at the outside of the plate. When operating on the front teeth, the handle being held angularly or tangentially thereto, the clearing-space will be thereby practically reduced in width, so that both sides of the thin front teeth and the adjacent portions of the plate will also be simultaneously and effectually cleansed. The mass *d* of bristles in its best form is longer than the main mass, be-

cause of the greater facility for cleansing in open tooth-spaces, which, as with many other points, would otherwise be practically inaccessible, and in its best form said mass is also tapered, 5 so as to afford a blunt wedge-shaped face at the tips of the bristles, so as to conveniently enable special scouring to be done at cavities in the plate and at angular junctions of the plate and teeth.

10 Although two of these masses of bristle tufts in one brush are generally ample for the purposes indicated, it is obvious that one or more additional masses may be employed, with either narrower or wider clearing-spaces between them, without departure from my invention— as, for instance, as illustrated in Fig. 3, wherein the wedge-shaped mass *d* is located between two main masses, *c*, one flat-faced and the other convex, as at *c'*, and the three masses 15 are separated by clearing-spaces *e* of different widths. This form of brush is especially adapted for dentists' use.

I am aware, as hereinbefore stated, that tooth-brushes have heretofore had isolated 25 masses of bristle tufts at the rear end of the handle and that floor-scrubbing brushes have had a main mass of bristle tufts in the head of the brush, and one or more rows of tufts

angularly set at the end of the brush-head, and projecting therefrom; but I know of no 30 prior tooth-brush or dental-plate brush specially provided with a clearing-space, whereby two adjacent masses of tufts may be simultaneously employed for cleansing oppositely-located surfaces.

Having thus described my invention, I claim as new and desire to secure by Letters Patent—

1. A dental-plate brush composed of masses of tufts of bristles separated by clearing-spaces, substantially as described, whereby 40 any two masses of bristles may co-operate in simultaneously cleansing two sides of a plate or the teeth thereon.

2. A dental-plate brush having masses of tufts of bristles separated by a clearing-space, 45 one of said masses being composed of bristles longer than those in the remainder of the brush, substantially as described.

3. A dental-plate brush having main masses of bristle tufts and a tapered mass of longer 50 tufts, each mass being separated from the other by a clearing-space, substantially as described.

ALANSON C. ESTABROOK.
